UNITED STATES PATENT OFFICE.

EMMET C. STANDIFORD, OF CHICAGO, ILLINOIS.

MOLD FOR CASTING.

SPECIFICATION forming part of Letters Patent No. 409,519, dated August 20, 1889.

Application filed January 13, 1888. Serial No. 260,618. (No model.)

To all whom it may concern:

Be it known that I, EMMET C. STANDIFORD, of Chicago, in the county of Cook and State of Illinois, have invented certain new and useful Improvements in Molds for Casting; and I do hereby declare that the following is a full, clear, and exact description thereof, reference being had to the accompanying drawings, and to the letters of reference marked thereon, which form a part of this specification.

This invention relates to molds for casting recessed or flanged blocks or plates—such, for instance, as stereotype-plates, the backing of electrotype-plates of that kind having flanges or ribs upon their rear or under surfaces, printers' furniture, or the like. Such molds usually consist of two or more parts, one of which parts contains the grooves or depressions constituting the mold proper.

Heretofore in casting electrotype and stereotype plates it has been necessary to make the flanges on said plates with a considerable flare or taper in order that the same may be easily withdrawn from the recesses of the mold after casting. This, however, makes the flanges of undesirable thickness and weight, and one of the objects of my invention is to provide means whereby said plates may be easily withdrawn from the mold when a thin flange of practically uniform thickness has been cast upon the same. To this end I provide the recessed part of the mold with a plurality of movable rods, plugs, or movable pieces adapted to act against the inner face of the cast plate, whereby the plates may be forced from engagement with the recesses of the mold without bending, distorting, or otherwise injuring them.

In Figure 1 of the accompanying drawings I have illustrated in a side view, partially in section, a casting block or mold, the upper member being shown raised in dotted lines at the upper right-hand corner, closed and in a horizontal position in full lines, and in position ready for casting in dotted lines. Fig. 2 is a transverse vertical section of the casting-block when in horizontal position, taken on line 2 2 of Fig. 1.

In the drawings, A indicates the bed-plate of the usual frame, which is provided with vertical standards A', connected by a pivot

or rod a, on which is mounted the lower half or plate B of the casting block or mold. The upper half B' of the block, which contains the 55 recesses, grooves, or depressions forming the mold proper, is hinged or pivoted at b to the plate B, the latter being held in horizontal position by engagement with a bell-crank lever C, pivoted at c to one of the standards A² 60 of the frame. The standards A² extend upwardly above the mold proper, and are connected by a rod a². The upper half B' of the block rests against this rod a², as illustrated in dotted lines in Fig. 1, when adjusting the 65 matrix C' upon the plate B before pouring.

D D indicate a series of bars or flat rods, which are placed within the grooves or recesses of the mold, and are arranged parallel with the flanges of the plates to be cast therein, so that they will bear against the entire length of the flanges of the cast plate. Said bars are pivoted within the mold at one end of the latter by means of a pivot-rod d, and are actuated to thrust the casting from the 75 mold by pressure exerted upon the ends of the said bars, which protrude from the opposite end of the mold. Said bars D D are shown as pivoted at d within the part B' of the mold, the lower edges of these bars forming the bottom of the grooves, in which the flanges of the cast plate are formed. The outer ends of the said bars D D are secured to a transverse bar or flanged plate D', which may be actuated to move all of the bars D D 85 at once.

B² B² are two standards, which rise from the plate B at opposite sides thereof. To the upper part of said standards are pivoted at e toggle arms or links E E, which latter are 90 pivotally connected at their lower ends with similar toggle arms or links E' E', which are pivoted at e' e' to the plate D'. The pivots joining the toggle-links E E' engage connecting-links E², which are pivoted to operating-levers, one of which is seen at E³, Fig. 1. Said operating-levers are pivoted at e³ to standards B³ B³ upon the plate B', and connected at their upper or outer ends by means of a cross-bar e², which forms a handle for the same. 95 100

Any suitable clamping device—such as the screw-dogs F F—may be used to lock the hinged part B' to the plate B when the mold is ready for pouring. When the matrix C' has been

placed on the plate B, which is flat or substantially flat, and the upper part B' or the mold proper locked thereon, the handle of the bell-crank lever C is moved upward against the 5 stop c' on the standard A', thus releasing the hinged end of the casting-block. The latter, swinging downward, assumes the inclined position illustrated in dotted lines in Fig. 1 and rests against the cross rod or stop a³, which 10 extends between the two standards A'. The hot metal is then poured into the mold at b⁸ over the matrix, and a stereotype or other plate (indicated by I in the drawings) thus formed. When the metal has sufficiently 15 cooled, the mold proper is brought back into the horizontal position, and the lever C again engages the end of the bed-plate and locks the same. The clamp or lock F is then released and the upper part B' of the mold may 20 be raised to the position shown in dotted lines, so as to rest against the stop a² on the standard A². The handle e³ of the toggle-levers E² may then be operated, and in doing so the toggles E E' force the plate D' toward the 25 movable half B' of the block, and the bars D D, attached to said plate D', will thus be caused to press the plate I from the mold. This operation may be performed, however, when the parts are in a horizontal position 30 and the half B' has been partially raised from the plate B.

Extending below the bars at their pivoted ends in the particular form of the device herein shown are short arms d' d', the ends 35 of which arms extend to the plate B. The upper half of the mold B' is cut away or recessed at proper intervals opposite each bar D, as shown at b⁵, for the reception of these short arms d', when the bars D are moved 40 within the mold for the purpose of pushing the plate I therefrom. Said arms d' form a portion of the mold, as shown, and prevent the hot metal when being poured into the mold from entering the recesses b³. In the 45 absence of such arms the metal would enter the said recesses in which the pivoted ends of the bars are inserted, and thus prevent movement of the same. The bars D obviously press their entire length against the flanges i 50 of the plate, and thus act with an equal pressure throughout the entire length of the same in forcing the latter from the mold.

The mold illustrated is adapted for casting four or more stereotype-plates of the width 55 of a column, the mold being extended to the matrix at b⁴ between the columns to divide the same, as shown.

I have herein shown a lever and toggle-links as a means for operating the movable

part or parts of the mold; but it is perfectly 60 obvious that a cam or other equivalent device may be thus used, and also that the movable part may be actuated by hand, by blows of a hammer or mallet, or otherwise. It will also be understood that the number of 65 bars D D required will depend upon the size of the plate to be cast. It is entirely obvious, furthermore, that the bars which act against the rear face of the casting may be stationary, and the main part of the mold may be 70 moved to disengage the casting therefrom, and a construction of this kind is therefore embraced within the scope of my invention.

I have herein shown my invention as embodied in a mold for casting stereotype- 75 plates. I do not, however, wish to limit myself to molds for casting stereotype-plates, inasmuch as the main features of my invention may be employed in casting the backing for electrotypes and in casting other plates 80 or blocks—such as printers' furniture—having flanges or provided with recesses therein, either when said recesses extend entirely through the plate, so as to form openings in the same, or when the recesses extend only 85 partially through the plate, as is the case with the stereotype-plate illustrated.

I claim as my invention—

1. The mold for stereotype or other plates, comprising a substantially flat part and a 90 grooved or longitudinally-recessed part, the latter part being provided with a plurality of movable bars located in the grooves or recesses and forming parts of the inner surface of the mold, said bars being hinged to the 95 said grooved or recessed part, a movable plate attached to all of said bars, and actuating devices for operating said movable plate, connected with said movable plate and the recessed part of the mold and acting to thrust 100 the said bars inwardly to free the casting from the mold, substantially as described.

2. The combination, with a mold comprising a substantially flat part and a recessed or grooved part with a movable part acting 105 upon the rear face of the casting, of an operating-lever pivoted to the recessed part of the mold and toggle-links pivoted to said recessed part and to said movable part, said operating-lever being connected with said toggle-links, substantially as described.

In testimony that I claim the foregoing as my invention I affix my signature in presence of two witnesses.
